WALTER H. TIBBALS, OF SYRACUSE, NEW YORK.

DISINFECTING APPARATUS.

1,215,218.

Specification of Letters Patent. Patented Feb. 6, 1917.

Application filed May 7, 1914. Serial No. 837,066.

To all whom it may concern:

Be it known that I, WALTER H. TIBBALS, of Syracuse, in the county of Onondaga, in the State of New York, have invented 5 new and useful Improvements in Disinfecting Apparatus, of which the following, taken in connection with the accompanying drawings, is a full, clear, and exact description.

10 This invention relates to certain improvements in disinfecting apparatus involving the use of a container for a germ or vermin destroying liquid and air under abnormal pressure and a pump extending into the 15 container and operable at will for producing and maintaining any degree of pressure desired.

One of the objects is to provide means whereby the confined liquid may be placed 20 under abnormal pressure through the same passage by which the liquid is permitted to escape, either from an external source of air compression or through the medium of the pump.

25 Another object is to enable the liquid to be discharged at regular or irregular intervals or in a continuous stream as the operator may elect or according to the conditions to be treated.

30 A further object is to make the piston rod hollow or tubular and to utilize the opening therethrough as a delivery passage for the liquid.

A still further object is to control communication between the interior of the 35 chamber and piston rod through the medium of a self-closing check valve normally preventing the passage of the liquid from the interior of the container into the tube.

40 Another object is to provide means actuated by the piston rod or piston when moved to a certain position for opening said valve and to place the piston rod under spring tension so that it will return 45 from such position when released to allow the valve to close.

A further object is to provide means for holding the piston rod and piston in the 50 position referred to for holding the valve open when it is desired to discharge the liquid in a continuous stream.

Other objects and uses relating to specific parts of the apparatus will be brought out in the following description.

55 In the drawings—

Figure 1 is a central vertical sectional

view of an apparatus embodying the various features of my invention except that a portion of the pump is shown in elevation.

Fig. 2 is a horizontal sectional view 60 through the lower end of the same device taken in the plane of line 2—2, Fig. 1.

Fig. 3 is an enlarged vertical sectional view of the lower end of the pump showing more particularly the check valve and stops 65 for holding the piston and piston rod in certain positions for opening the check valve and permitting it to close.

Fig. 4 is a horizontal sectional view 70 through the lower end of the pump taken in line 4—4, Fig. 2.

Fig. 5 is a perspective view of the inner end of the piston rod.

The apparatus shown comprises a cylindrical container —1— having end heads 75 —2— and —3— secured thereto in such manner as to form air and liquid tight joints capable of withstanding the pressure under which the liquid as —a— is confined.

The head —3— is provided with a central hollow bushing —4— firmly secured in place to form an air and liquid tight joint and threaded internally for receiving a screw cap —5— having wings —6— by which it may be secured in place with sufficient firmness to prevent leakage of air or liquid at the screw joint.

This cap is provided with a central socket opening from its inner end in which is secured by brazing, soldering or other air- and water-tight connections a pump cylinder —7— having its opposite end extending to a point in proximity to the opposite end head —2— and provided with a passage way —8— communicating with the interior of 95 the container.

A check valve —9— is located in the passageway —8— and is normally closed by a spring —10— to cut off communication between the interior of the pump cylinder and 100 container.

Within the pump cylinder is movable a piston —11— having a tubular piston rod —12— extending outwardly through a gland —13— in the cap —5—, the inner end of the 105 piston rod being extended beyond the piston and provided with branch passages —14— for establishing communication between the interior of the container and lengthwise opening through the tube through the 110 medium of the passage —8— when the valve —9— is opened.

The means for opening the valve consists of a stem —15— on the lower end of the piston rod —12— and of such size as to enter the upper end of the passage —8— and force the valve —9— from its seat against the action of the spring —10— when the piston rod and piston are moved to a certain position, in this instance to approximately the end of their inward stroke.

10 Suitable means is provided for locking the piston rod and piston in two different positions at different distances from the seat of the valve —9—, the locking means for the innermost position serving to hold the valve 15 open, as for example, in projecting a continuous stream from the discharge nozzle hereinafter described, while the other locking means serves to prevent outward movement of the piston from that position and at 20 the same time permitting the valve to close and allowing the piston to be moved inwardly in limited distance to intermittently open the valve against the action of a retracting spring —16— surrounding the outer 25 end of the piston rod as shown more clearly in Fig. 1.

For this purpose, the inner end of the piston rod adjacent the stem —15— is provided with laterally projecting lugs or shoulders 30 —17— at diametrically opposite sides of the axis of the piston rod for interlocking engagement with separate sides of diametrically opposite segmental flanges —18— and —19— projecting inwardly from the inner 35 end of the pump cylinder at different distances from the seat of the valve —9— between such valve seat and the piston —11—, the flanges of one set being disposed at right angles to those of the other set.

40 In other words, the flanges —18— on the outer set farthest from the seat of the valve —9— are diametrically opposite each other and spaced apart a certain distance to receive the lugs —17— between them when 45 turned at right angles thereto, thus permitting the lugs to be brought into interlocking engagement with the under sides of the flanges by moving the piston rod and piston inwardly and then turning to such position 50 that the lugs —17— will be registered with the space below the flanges —18— and by then turning the piston rod and piston a quarter turn more or less until the said lugs ride under said flanges, thereby holding the 55 piston rod and piston against outward movement by the retracting spring —16— which is then under compression, it being understood that the distance between the inner end of the stem —15— and plane of 60 the lugs —17— is less than the distance between the seat of the valve —9— and inner faces of the flanges —18— to allow the valve to close.

The inner flanges —19— are spaced apart 15 from the outer flanges a sufficient distance to

permit the lugs —17— to pass between them and are also spaced apart from the seat of the valve —9— a sufficient distance to permit the lugs to ride under them, but the distance between the seat of the valve —9— and underside of the flanges is somewhat less than the distance between the inner end of the stem —15— and lugs —17— so that when the lugs are interlocked with the flanges —19—, the inner end of the stem —15— will 75 engage and open the valve —9—, thereby establishing direct communication between the interior of the container —1— and tubular piston rod —12— to allow the liquid to pass from the container through the passage —8— and branch openings —14— and thence through the tubular piston rod to the exterior of the container where it may be directed as required in a manner presently described.

80 Secured to the outer end of the piston rod is a cross rod —20— serving the triple purpose of a handle, a valve case and a discharge nozzle, and for this purpose is provided with a central, though relatively small, delivery passage —21— leading from a central valve chamber —22— through one end of the handle —20—, said valve chamber communicating with the interior of the adjacent end of the piston rod —12—.

90 The inner end of the relatively small passage —21— adjacent the valve chamber —22— is provided with a valve seat for a needle valve —23— which is screwed in the opposite end of the handle and provided with a hand-piece —24— by which the needle valve may be opened and closed at the will of the operator.

100 The spring —16— is interposed between the outer end of the cap —5— and inner face of the handle —20— on the outer end of the piston rod and is relatively short as compared with the length of the piston rod but of sufficient length to be placed under compression when the lugs —17— on the inner end of the piston rod are interlocked with either the flanges —18— or —19— so that, when the lugs are disengaged from either set of flanges, the spring will automatically force the piston and piston rod outwardly a limited distance corresponding to the expansive force of the spring.

110 The object of the outer set of locking flanges —18— is to hold the stem on the inner end of the piston rod in relatively close proximity to the normally closed valve —9— so that when the needle valve —23— is opened, the valve —9— will be normally closed and prevent the passage of the liquid from the container into the tubular piston rod and at the same time permitting the piston rod to be moved inwardly by pressure of the hand upon the handle —20— against the action of the spring —16— sufficient to cause the stem —15— to open the valve 120 125 130

—9— and thereby allow the liquid to escape from the interior of the container through the opening in the piston rod and thence outwardly through the delivery passage 5 —21— to the particular locality to be treated.

The normally closed valve —9— may thus be intermittently opened and closed at regular or irregular intervals or may be held 10 open for indefinite periods against the action of the spring —16— to enable the operator to project intermittently or continuously in a stream or spray where most effective.

On the other hand, if it is desired to project a continuous stream without further attention from the operator, he may push the piston rod inwardly a sufficient distance to bring the lugs —17— beneath the flanges —19— and then turn the piston rod a quarter 20 turn to interlock said lugs with said flanges, in which position, the stem —15— will engage and hold the valve —9— open and permit the operator to control the exit of the liquid through the passage —21— 25 voluntarily by means of the needle valve —23— by which the liquid may be discharged in the form of a stream or spray according to the adjustment of the needle valve.

30 In filling the container with liquid, the cap —5— is unscrewed and the entire pump mechanism withdrawn therewith out of the container whereupon the disinfecting liquid may be introduced in any desired manner 35 through the central opening in the head —3— until the container is approximately two-thirds full, whereupon the pump and cap are re-inserted into the container and tightly secured in place to prevent leakage. 40 Air or other elastic fluid is then introduced under abnormal pressure into the remaining space in the container either by connecting the delivery end of the handle —21— to an external source of compressed air and then 45 opening the needle valve —23— to allow the compressed air to pass into the container through the passage —21—, tubular piston rod —20— and passage —8—, or this pressure may be produced by the operation of 50 the pump by closing the needle valve —23— and then operating the piston through the medium of the handle —20— until the desired pressure is obtained, whereupon the piston rod may be forced inwardly to approximately 55 the limit of the inward stroke, and its lugs —17— on the inner end thereof brought into interlocking engagement with the flanges —18— or —19—, thereby reducing to a minimum the space occupied by the 60 entire apparatus and placing it in condition for immediate action to discharge the liquid in the manner previously described.

What I claim is:

1. In an apparatus of the character described, a container for liquid and air, a

piston pump having a cylinder extending from one end of the container to a point in proximity to its opposite end and also having a tubular piston-rod in constantly open communication with the interior of the cylinder at a point beyond the inner end of the piston, said cylinder having a passage in its inner end opening into the container, a self-closing valve controlling such passage, means secured to the inner end of the tubular piston rod for opening said valve as the piston approaches the limit of its inward stroke for permitting the passage of the liquid through the tubular piston-rod, and means on the outer end of the tubular piston-rod for controlling the escape of the liquid therefrom.

2. In a device of the character described, the combination of a container, a hand-operated piston pump extending thereinto and having an outlet in its handle, said pump having a piston rod provided with a valveless passage connecting the inlet and outlet, a valve in the handle controlling the outlet, a single self-closing valve controlling the flow of liquid from the container through the inlet and into said passage, and means actuated by the piston when moved to a certain position for opening the self-closing valve.

3. In an apparatus of the class described, a container for liquid and air, a pump cylinder secured in one end of the container and extending to a point in proximity to the opposite end and having its inner end provided with a passage communicating with the interior of the container, a self-closing valve in said passage, a piston movable in the cylinder and provided with a tubular piston-rod extending through the outer end of the cylinder and container and having its inner end provided with an opening at the inner end of the piston and in constantly open communication with said passage and also provided with means rigid thereon for opening the valve as the rod approaches the limit of its inward movement to allow the liquid to pass out through the tubular rod, a handle on the outer end of the tubular rod having a discharge passage, and a valve in the handle controlling said discharge passage.

4. In a device of the character described, a container for liquid and air under pressure, a pump cylinder secured to one end of the container and extending to a point in proximity to the opposite end and having its inner end provided with a passage connecting the interior of the cylinder with the interior of the container, a self-closing valve in the passage, a piston and hollow piston-rod therefor having an opening at the inner end of the piston in constantly open communication with said passage, said piston-rod having its inner end provided with means

for opening the valve when the rod is at the limit of its inward movement, coöperative locking devices on the inner ends of the piston-rod and cylinder, respectively, adapted to be brought into interlocking engagement with each other by the turning of the rod for holding said rod in its innermost position and thereby holding the valve open, a handle on the outer end of the rod having a discharge passage, and a valve in the handle for controlling said discharge passage.

5. In an apparatus of the class described, a fluid container, a pump cylinder secured in one end of the container and extending to a point near the opposite end, said cylinder having its inner end provided with a passage opening into the interior of the container, a self-closing valve in said passage, a piston, a tubular piston rod extending through the outer end of the cylinder and communicating at all times with said passage at a point between the piston and valve, means actuated by the piston rod when moved to a certain position for opening said valve, a handle on the outer end of the piston rod having a delivery passage, and a valve for the delivery passage.

6. In a device of the character described, the combination of a container, a hand-operated piston pump, extending thereinto and having an inlet in the inner end of its cylinder and an outlet in its handle, said pump having a piston rod provided with a valve-less passage connecting the inlet and outlet, a valve in the handle controlling the outlet, a single self-closing valve controlling the

flow of liquid from the container through the inlet and into said passage, means actuated by the piston when moved to a certain position for opening the self-closing valve, 40 and means for locking the piston in such position to hold the last-named valve open.

7. In a device of the character described, the combination of a container, a hand-operated piston pump having an inlet passage 45 within the container and an outlet passage external thereto, said pump having its piston rod provided with a lengthwise passage connecting the inlet and outlet passages, a check valve in the inlet passage, a manually-operated valve in the outlet passage, and means actuated by the piston when moved to a certain position for opening the check valve.

8. In a device of the character described, 55 the combination of a container, a hand-operated piston pump having an inlet passage within the container and an outlet passage external thereto, said pump having its piston rod provided with a lengthwise passage connecting the inlet and outlet passages, a check valve in the inlet passage, a manually-operated valve in the outlet passage, means actuated by the piston when moved to a certain position for opening the check valve, and 60 means for locking the piston in such position to hold the check valve open.

In witness whereof I have hereunto set my hand this 28th day of April, 1914.

WALTER H. TIBBALS.
